UNITED STATES PATENT OFFICE.

JAMES JOPLING, OF WHAT CHEER, IOWA.

COAL-CHUTE.

SPECIFICATION forming part of Letters Patent No. 352,694, dated November 16, 1886.

Application filed March 30, 1886. Serial No. 197,130. (No model.)

To all whom it may concern:

Be it known that I, JAMES JOPLING, of What Cheer, in the county of Keokuk and State of Iowa, have invented a new and Improved 5 Coal-Chute, of which the following is a full, clear, and exact description.

The object of my invention is to provide a new and improved coal-heaver for loading box or flat cars with coal or other material without 10 moving the cars.

The invention consists of a sliding and laterally-adjustable scuttle in connection with an inclined chute and an intermediate hinged curved plate, and of devices for operating the 15 scuttle and the hinged plate.

The invention also consists of various parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a front elevation of my improvement. Fig. 2 is a longitudinal sectional elevation of the same, on the line *xx* of Fig. 1. Fig. 3 is a detail front view of the same, parts being removed.

My improved coal-heaver is mounted on a 30 frame, A, of suitable construction, provided with a stationary chute, B, which is curved or semicircular on its lower half, and to the extreme lower end of which chute is connected a 35 hinged curved plate, C. To each side of the outer end of the plate C is attached a chain, D, which passes over a pulley, E, attached to the timbers of the frame A, and each chain D is provided on its other end with a balancing-weight, F. A curved scuttle, G, conforming 40 in shape at its upper end to the curved plate C, is placed next to the curved plate C and is pivoted to a block or slide, H, held adjustably by means of a set-screw, H', on a square bar, I, running below and parallel with the chute B, 45 and being guided in bearings J, sliding in curved recesses or grooves K, formed in the cross-beams A' and A² of the frame A. The lower end of the bar I is provided with an adjustable casting, L, through a recess of which 50 passes a segment, G', having apertures G² and being secured to the bottom of the scuttle G.

A pin, M, passes through the casting L and through one of the apertures G² in the segment G', so as to hold the scuttle G in a position parallel with and inclined to the bar I. Each 55 of the bearings J is provided on each side with lugs J' and J², to each of which is attached a chain, J³, which pass over guide-rollers N upward to a windlass, N', mounted on the standards N², attached to the platform A³, 60 formed on the frame A. The windlass N is provided with a crank-arm, O, which can be held in any desired position by a pin, P, inserted in one of the apertures P' in the frontstandard, N². An arm, Q, held adjustably on the bar I by a 65 set-screw, is provided on its lower end with a ring, Q', to which is attached a chain, R, which passes over guide-rollers S, upward and around a windlass, T, mounted on standards T', secured to the platform A³. The windlass T is 70 provided with a crank-arm, U, which can be held in position by a pin, V, inserted in one of the apertures T² in the standard T'.

The operation is as follows: In order that every part of a car may be loaded with coal it 75 is necessary to move the scuttle G from one end of the car to the other, so as to avoid moving the car. The scuttle is moved to one side by turning the crank-arm O so that one of the chains J³ pulls on its respective lug J' or J² on the bearing J, which slides in the curved grooves K, and the chain is wound up on the windlass N' while the other chain unwinds correspondingly from the same windlass. The scuttle can be made to slide up or down in 80 line with the curved chute B by turning the handle U of the windlass T, so that the latter winds up the chain R, which pulls on the arm Q, attached to the bar I, and thereby slides the latter, which carries the scuttle G on 85 the bearings J. The intermediate connecting curved plate, C, can be disconnected from the chute B, and the scuttle G and the chute B can be brought into direct connection with each other wherever desired. It will be seen 90 that when the scuttle G is moved to the right the coal coming down the chute B will pass to the left of the car, and when the scuttle G is moved to the left the coal will pass over to the right of the car, so that every part of the car 95 can be loaded with coal by the operator standing on the platform A³ and working the wind- 100

lasses N' and T, as desired. The scuttle G can be raised to any desired height by inserting the pins M in the apertures G² in the segment G'.

5 Having thus fully described my invention, I claim as new, and desire to secure by Letters Patent—

1. The combination, with the chute having a rounded or curved portion at its forward end, of a scuttle curved to correspond to the curved end of the chute, and a longitudinally and laterally movable rod, connected to the said scuttle, whereby the scuttle may be moved longitudinally or laterally in the arc described by the curved end of the chute, substantially as set forth.

2. The combination, with the chute, of the longitudinally-sliding rod, horizontally-movable bearings therefor, curved ways for said bearings, means for operating the rod, and a scuttle hinged to swing vertically on the forward end of the said bar, substantially as set forth.

3. In a coal-heaver, the combination of the chute B and the scuttle G, hinged to the block H, and the segment G', with the bar I, the adjustable block H, the casting L, and the pin M, substantially as shown and described.

4. In a coal-heaver, the combination of the scuttle G, hinged to the block H, the segment G', the casting L, the pin M, and the bar I, with the bearings J, sliding in the grooves K in the cross-beams A' and A², and the chains J³, wound upon the windlass N', substantially as shown and described.

5. In a coal-heaver, the combination of the scuttle G, pivoted to the block H, the bar I, and the bearings J, sliding in the grooves K and provided with the lugs J' and J², with the chains J³, the windlass N', the crank-arm O, 40 mounted on the standards N², having apertures P', and the pin P, substantially as shown and described.

6. In a coal-heaver, the combination of the scuttle G, pivoted to the block H, the bar I, 45 and the bearings J, sliding in the grooves K and provided with the lugs J' and J², with the adjustable arm Q, the rope R, passing over the guide-rollers S, the windlass T, mounted on the standards T', having the apertures T², the 50 crank-arm U, and the pin V, substantially as shown and described.

7. In a coal-heaver, the combination of the chute B, the hinged plate C, the scuttle G, pivoted to the block H, the segment G', having 55 apertures G², the casting L, the pin M, and the bar I, sliding in the bearings J, with the bearings J, the chains J³, the windlass N', the crank-arm O, the arm Q, the chain R, the windlass T, and the crank-arm U, substantially as shown and described.

8. In a coal-heaver, the combination of the inclined chute B, made semicircular in its lower half, with the hinged curved plate C, the chains D, the pulleys E, and the weight 65 F, substantially as shown and described.

JAMES JOPLING.
